UNITED STATES PATENT OFFICE.

ALBERT HOLLAND SCROXTON, OF BATTERSEA, LONDON, AND WILLIAM HANDEL CANNON, OF LONDON, ENGLAND.

APPARATUS FOR CLEANSING TEXTILE FABRICS.

No. 852,804.

Specification of Letters Patent.

Patented May 7, 1907.

Application filed November 4, 1904. Serial No. 231,435.

To all whom it may concern:

Be it known that we, ALBERT HOLLAND SCROXTON and WILLIAM HANDEL CANNON, subjects of the King of the United Kingdom of Great Britain and Ireland, residing, respectively, at 33 Russell Street, Battersea, London, and 19 Wool Exchange, Coleman street, in the city of London, both in the county of London, in that part of the United Kingdom called England, have invented a new and improved construction of apparatus for cleansing textile fabrics, applicable also for insuring circulation of water in boilers and for like purposes, of which the following is a specification.

This invention relates to an apparatus to be placed or fixed in boilers, and other receptacles in which a liquid is heated to insure a rapid constant and efficient circulation of the liquid contained therein, and is specially applicable to coppers where textile fabrics such as wearing apparel are boiled and whereby after a cleansing agent such as soap or soap powder is applied, the clothes are sufficiently deprived of their dirt and stains without injuring the fabric in any way.

For the purpose of this invention we will describe same as applied to a copper for washing clothes, and the construction of apparatus will be clearly understood from the following description aided by the accompanying drawings in which,

Figure 1 is an elevation of the apparatus complete. Fig. 2 is a longitudinal section of same, and, Fig. 3 a plan.

The apparatus consists of a hollow base A provided with holes B and a conical orifice C. Surrounding the conical orifice C is a collar D provided with a bayonet joint E, said collar being for receiving a detachable tube F which is secured to the collar by its pin G entering the bayonet joint E in the usual manner.

The tube F is provided at the top with a deflector H, and in the interior is situated a conical lining I which runs from the base of the tube F to about beyond mid distance of the height of the tube F where the lining I terminates with a smaller opening. This lining I is hermetically sealed to the tube at base and at its apex is hermetically sealed to an inverted cone shaped lining J this being hermetically sealed to the tube F at the top so

as to provide an hermetically sealed chamber K between the two linings I, J, and the tube F.

This apparatus is placed in the washing copper which has the necessary cleansing liquid and agents and surrounded by the clothes to be cleansed. As the water is heated principally under the hollow base, convection currents will be set up and be deflected through the conical orifice up the tube thus causing the air in the chamber K to be heated and prevent the inner conical linings from becoming cooled by the clothes around the tube F, thereby causing a different temperature within the conical linings to that outside the tube which in conjunction with the convection currents will cause an ascending current to take place within the tube and be projected from the top by the deflector H on to the top of the clothes.

By employing the two conical linings C and I the liquid leaves the contracted orifices of the linings C and I with great force and this is greatly assisted by the heating of the air in chamber K so that the water is deflected downward with great pressure causing it to thoroughly attack the clothes and efficiently cleanse them.

The dirt extracted from the clothes passes into the apparatus and becomes deposited on the lining I and flows down between the cone orifice C and the tube where it is retained during the working of the apparatus and can be removed when the apparatus is taken to pieces.

A ball L may be employed in the inverted lining J for action on the orifice of the lining I to prevent any back action of the flow of the liquid.

The conical orifice C may be arranged so as to be fitted to or form part of the tube F.

By this invention the force of the liquid is much increased and in consequence the clothes are better acted upon for cleansing purposes.

What we claim as our invention and desire to secure by Letters Patent is:—

1. In apparatus for cleansing textile fabrics the combination of a hollow base provided with perforations and a conical orifice, a detachable tube surrounding said conical orifice and provided with a lining consisting of a lower conical member and an upper in-

verted conical member and a deflector connected to the top of said tube as herein set forth.

2. In apparatus for cleansing textile fabrics the combination of a hollow base provided with perforations and a conical orifice, a detachable tube surrounding said conical orifice, and provided with a lining consisting of a lower conical member and an upper inverted conical member with a hermetically sealed air chamber between said tube and

lining, a ball acting at the junction of the conical members and a deflector attached to the top of said tube as set forth.

In testimony whereof we have signed our names to this specification in the presence of two subscribing witnesses,

ALBERT HOLLAND SCROXTON.

WILLIAM HANDEL CANNON.
